UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

CHUCK-CO尤LING.

1,208,224.

Specification of Letters Patent. Patented Dec. 12, 1916.

Application filed August 21, 1914. Serial No. 857,917.

To all whom it may concern:

Be it known that I, WILLIAM A. SMITH, a citizen of the United States, residing at Denver, in the county of Denver and State 5 of Colorado, have invented new and useful Improvements in Chuck-Couplings, of which the following is a specification.

The present invention relates to means for coupling two members together, preferably rotatable members, and in a more specific aspect is designed particularly for mounting the drill bit of a rock drilling machine in the chuck of such machine.

The primary object is to provide a simple and practicable device of a novel character for the above purposes.

The preferred embodiment of the invention, is illustrated in the accompanying drawings, wherein:

20 Figure 1 is a longitudinal sectional view through the coupling. Fig. 2 is a cross sectional view on the line 2—2 of Fig. 1. Fig. 3 is a cross sectional view on the line 3—3 of Fig. 1. Fig. 4 is a detail perspective view 25 of the members in coupled relation, with portions thereof broken away. Fig. 5 is a sectional view taken on the line 5—5 of Fig. 2, looking in the direction of the arrow and with the detachable member partially with- 30 drawn.

Similar reference numerals designate corresponding parts in all the figures of the drawings.

In the embodiment illustrated, a tubular support 6 is disclosed, having a tubular plug 7 in one end and containing a rotatable member 8, this member being provided with gear teeth 9 at one end, by which it can be suitably rotated.

40 The member 8 projects beyond the support 6, and is provided with a longitudinal socket 10 that is angular in cross section—preferably square. This angular socket opens through the front or projecting end 45 of the member 8. Said member 8 is also provided with longitudinally elongated slots 11 cut entirely through the same, and communicating with the socket in rear of the open mouth thereof. These slots are 50 tangential to the axis of the member 8 and are at an acute angle to the walls of the socket, which they intersect, as will be evident by reference to Fig. 2. They thus produce internal recesses or clearance spaces in 55 the walls of the socket, and their longer

faces 12 constitute stop shoulders, as herein-after pointed out.

The other member to be coupled is designated 13, and while it may be of any desired cross sectional shape, in the embodiment 60 shown, it is cylindrical and has an angular enlargement 14, the cross sectional area of which corresponds substantially to that of the socket 10. This angular enlargement 14 will thus pass through the open mouth 65 of the socket 10, and when in line with the slots 11, it can be partially rotated in said socket, because the inner ends of the slots constitute clearance spaces, as above described. The amount of rotation is, however, limited by the walls 12 of the slots 70 which constitute stop shoulders in the path of the faces of said angular enlargement. It will furthermore be noted that when the angular enlargement thus bears against said 75 stop shoulders 12, the corners will be out of line with the socket and the two members 8 and 13 are interlocked against withdrawal from each other. It will also be seen by reference to Fig. 1 that the slots 11 are 80 considerably longer than the enlargement 14, so that the two members 8 and 13 are capable of a limited relative movement. The portion of the member 8 in rear of the socket is formed with a bore 15, through 85 which the rear end of the member 13 projects, and a tappet 16, located in the plug 7, constitutes means for transmitting blows to the rear end of the member 13, as will be 90 evident.

From the foregoing, it is thought that the construction, operation, and many advantages of the herein described invention will be apparent to those skilled in the art, without further description, and it will be understood that various changes in the size, shape, proportion and minor details of construction may be resorted to without departing from the spirit or scope of the invention.

Having thus fully described my invention, what I claim as new, and desire to secure by Letters Patent, is:

1. In a structure of the character set forth, two members to be coupled, one of said members having an open-ended socket that is angular in cross section, and internal recesses in the walls of said socket, forming stop shoulders, the other member having an angular portion that enters the open end of 110

the socket and is partially rotatable therein, the stop shoulders engaging said angular portion and limiting the rotation of the same in the socket.

5 2. In a structure of the character set forth, two members to be coupled, one of said members having a socket provided with an angular mouth, and internal recesses in the walls of said socket, forming stop shoulders, the other member having an angular portion that substantially corresponds to the angular mouth of the socket and enters the same, said angular portion being partially rotatable within the socket and bearing 10 against the stop shoulders, to limit such rotation, and said member when so rotated being interlocked against withdrawal from the socket.

3. In a structure of the character set forth, 20 two members to be coupled, one of said members having a socket that is of angular cross section and having an open mouth and being of substantially the same cross sectional area in rear of the mouth, said socket having internal recesses forming clearance spaces, and stop shoulders, the other member having an enlarged angular portion that is movable through the angular mouth of the socket into the same and is partially rotatable with- 25 in the socket and recesses, abutting against the stop shoulders to limit such rotation, said recesses being longer than the angular enlargement to permit a limited longitudinal play.

35 4. In a structure of the character set forth, two members to be coupled, one having a socket provided with an open mouth and a slot cut into said member and intersecting the socket, forming a stop shoulder, the 40 other member having a portion entering the socket and partially rotatable therein, said latter member having a portion that abuts against the wall of the slot and limits the said rotation.

45 5. In a structure of the character set forth, two members to be coupled one having a socket provided with an open mouth, and a tangential slot cut into said member and intersecting the socket, forming a clear- 50 ance space and a stop shoulder, the other

member having an angular portion that enters the socket and is partially rotatable therein and in the slot, said latter member abutting against the stop shoulder.

6. In a structure of the character set forth, 55 two members to be coupled, one having a socket that is angular in cross section, and slots cut into the member and intersecting the walls of said socket, forming clearance spaces and stop shoulders, the other member 60 having an enlarged portion that is angular in cross section and removably engages in the socket, said angular portion being rotatable within the socket and in the slots and abutting against the walls of said slots. 65

7. In a structure of the character set forth, 70 two members to be coupled, one having a socket that is angular in cross section, and slots cut through said member and intersecting the walls of the socket at an acute 75 angle, the other member having an angular portion that detachably engages in the socket and is partially rotatable therein and in the slots, the walls of said slots constituting stop shoulders against which the angular faces of 75 the last mentioned member abuts.

8. In a structure of the character set forth, 80 a rotatable member having a socket that is angular in cross section and opening through one end of said member, and elongated slots cut through the member and intersecting the walls of the socket at an acute angle thereto, forming clearance spaces and stop shoulders, and another member having an angular enlargement, the cross sectional 85 area of which corresponds substantially to the cross sectional area of the socket, said enlargement removably engaging in the socket and being partially rotatable therein, the face of said enlargement when so rotated 90 abuting against the stop shoulders and the angular enlargement being then interlocked in the socket against withdrawal.

In testimony whereof I have hereunto set my hand in presence of two subscribing witnesses. 95

WILLIAM A. SMITH.
